DESIGN FOR A TABLE

Ray Rice, New York, and Henry Jensen,
Brooklyn, N. Y.

Application August 8, 1934, Serial No. 52,863

Term of patent 14 years

To all whom it may concern:

Be it known that we, RAY RICE, a citizen of U. S. A., and HENRY JENSEN, a German subject, residing at New York city, in the county of New York and State of New York, and at New York city, Borough of Brooklyn, in the county of Kings and State of New York, respectively, have invented a new, original, and ornamental Design for Tables, of which the following is a specification, reference

being had to the accompanying drawing, forming part thereof, wherein,

Figure 1 is a front perspective view of a table showing our design.

Figure 2 is a side perspective view of the same.

Figure 3 is a rear perspective view of the same. We claim:

The ornamental design for a table as shown.

RAY RICE.
HENRY JENSEN.
